ORTHOPEDIC SUPPORTIVE FRAME

Moyer M. Safford, Schenectady, N.Y., assignor to General Electric Company, a corporation of New York
Filed Apr. 29, 1966, Ser. No. 546,299
2 Claims. (Cl. 272—57)

ABSTRACT OF THE DISCLOSURE

An exercising device is described for use by paraplegic patients, who require buildup of trunk and hip muscles. A single enclosing girding member, at least three extensible support members depending therefrom and a stabilizer base connected to the lower ends of these support members cooperate to maintain a paraplegic patient (with lower extremities supported by separate artificial support means) in the erect position during the performance of physical exercise. The girding member is composed of at least two arcuate pieces. One of the arcuate pieces hinged to the balance of the girding member has a given single support member attached thereto. By detaching the given single support member from the stabilizer base, separating one end of the one arcuate piece from the balance of the girding member and rotating the one arcuate piece together with the given single support member attached thereto about the hinged connection, access for the patient into the girding member is readily provided.

This invention relates to improvements in apparatuses for aiding the neuromuscular re-education of individuals suffering from paraplegia, wherein the entire lower half of the body is affected with motor and sensory paralysis.

For those patients possessed of good physical development and muscle tone at the time of the onset of paraplegia, as for example may occur from accidental damage to the spine, conventional physical therapy devices, such as parallel bars, wheel chairs, and exercising mats may be beneficially employed very soon after onset of this condition. However, in the case of paraplegia in a tall heavy person, in a person possessed of only very poor muscle tone because of obesity, age, etc., or in a poorly coordinated individual, conventional physical training devices are usually beyond the muscular capacity of such people until after they have developed the requisite muscle power, particularly in the region of the trunk and hips. Unfortunately, for such paraplegics in very poor physical condition the transition to a state of improved muscular power is greatly hampered by the very limited opportunity for such patients to be exposed to any exercises other than passive, single-muscle exercises. The most useful exercises for neuromuscular re-education and buildup of muscle power require the patient to be in the standing position and actively participate. For such patients, support with limited freedom of movement in the vertical position has been an insurmountable problem, not only because of the patient's very real fear of falling and receiving further injury, but also because the long leg braces that must be worn to maintain the patient erect add considerably to the weight of the patient setting even higher demands for the stability of the supporting apparatus.

The aforementioned long leg braces from which paraplegic patients receive support for standing, lock at the knees and the hips to prevent collapse of the standing patient by bending at the knees or toppling over by jacking at the mid-section. Once having been moved to the erect position, such a patient, when strong enough, can gain a degree of mobility using crutches by employing a motion in which both legs are swung forward at the same time to a forward position, after which the crutches

2

are moved to a more advanced forward position for a new swinging motion.

As is well recognized, this method of locomotion is very awkward and requires constant reliance on crutches. However, for such a patient to be able to attempt to retrain the neuromuscular mechanism for the walking exercise, which requires the extension of one leg at a time to a position further ahead of the other leg, the hip lock (upper slip lock) of the long leg braces must be unlocked to enable the necessary independent swinging motion of the legs. If the patient does not have sufficient strength in the trunk and hip muscles for self-support of the upper part of the body, he will immediately jackknife upon loss of the rigid support received from the long leg braces with the upper slip lock in the locked position.

Thus, for the type of patient referred to hereinabove a program of neuromuscular re-education must precede the removal of this hip restraint and the prime object of this invention is the provision of a device to insure a safe and stable environment for the patient during this period of neuromuscular re-education of the muscles of the trunk and hip regions in order to "upgrade" the patient physically by techniques of proprioceptive neuromuscular facilitation to the point at which such a patient can profitably employ conventional therapeutic exercise devices and techniques.

The philosophy of the treatment known as "proprioceptive neuromuscular facilitation" is succinctly presented in the text book "Proprioceptive Neuromuscular Facilitation—Patterns and Techniques" by Knott and Voss (copyright 1956, Paul B. Hoeber, Inc., Library of Congress Catalog Card No. 56-5604) in column 2 of page 1. As stated therein this is a philosophy of muscular treatment "based upon the ideas that all human beings respond in accordance with demand; that existing potentials may be developed more fully; that movements must be specific and directed toward a goal; that activity is necessary to the best development of strength, coordination, and endurance; and that the stronger parts strengthening weaker parts through cooperation lead toward a goal of optimum function".

The device of this invention has been shown to enable paraplegic patients, who require muscular buildup of trunk and hip muscles to receive proprioceptive neuromuscular facilitation while using this device wherein vertically adjustable girding means are employed in combination with, and supported on, stabilizing means such that the patient's own weight is employed to increase the stability of the device and obviate overturning thereof.

The unexpected advantages gained by the ability of this device to permit paraplegics to engage in a confident manner in proprioceptive neuromuscular facilitation of the trunk and hip muscles and simultaneously to stimulate the activity of the neuromuscular network of the lower extremities which are supported, but not held immobile in the long leg braces, is well illustrated by the fact that this device has been built for, and used by, a patient suffering from a traumatic paraplegia secondary to the compression fracture of a portion of the spinal column, which occurred in an automobile accident. This patient was a tall, very heavy man of middle age in poor physical condition. Attempts at neuromuscular re-education of this patient over a period of eight months produced only slight improvement as indicated by muscle examinations conducted during this period. This substantial failure to progress is believed to have been due to the patient's inability to adapt to and properly utilize conventional training equipment, because of his pronounced apprehension and insecurity, which in turn appear to have been the products of his poor physical con-

dition at the time of the onset of paraplegia. At this point, in time, the device described herein was invented and constructed specifically for this patient. The patient was periodically placed erect (supported by long leg braces) within the girt of the instant device and from this secure erect position he could engage in complex activities, which require the simultaneous use of both hands, arms and shoulders, as for example, catching and throwing a basket ball. In this way the patient was encouraged and enabled to directly use and strengthen multiple sets of muscles in the trunk and neck and by stimulation to facilitate neuromuscular responses in the hip, knee, and even the ankle. In contrast to the preceding unproductive eight month period, a period of one month of activity in the device of the instant invention provided substantial improvement.

Therefore, the contribution of this improvement in therapeutic devices is its capacity to support the paraplegic patient (already equipped with long leg braces) in an erect position with a degree of freedom enabling active participation by the patient in many complex motion activities using the muscles of the upper portion of the body to develop new abilities and greater strength and endurance in the patient rather than limiting the patient to largely straight motion activities.

Further, such patients can be gainfully employed at job tasks, which must be executed in an erect position, at a much earlier stage than would otherwise be possible thereby regaining for the patient a wage earning capacity. In order to provide for such use of this device, construction features have been incorporated therein to make the device easily portable.

This device offers the additional advantage of enabling safe, vertical positioning of a paraplegic patient as required to minimize the incidence of sores and similar discomforts accompanying constant occupancy of a bed or wheel chair.

After the trunk muscles have been improved to a substantial degree the girt can be lowered to permit even greater spiral and diagonal body motion. Then, when the hip muscles have gained sufficient strength the height of the leg braces can be reduced eliminating the former hip support and the patient, still relying upon orthopedic supportive frame, can continue strengthening the muscles of the hips and of lower extremities with the rotative multi-muscle exercises promoting proprioceptive stimulation.

Other objects and many of the attendant advantages of this invention will be readily appreciated as the same become better understood by reference to the following detailed description when considered in connection with the accompany drawings in which like reference numerals designate like parts throughout the figures thereof and wherein:

FIG. 1 is a top plan view of the invention;

FIG. 2 is a side view thereof;

FIG. 3 shows the adjustable supports for the girt in greater detail and in partial cross-section, and

FIG. 4 shows a partial bottom view of the stabilizing base.

As shown in the drawings, the orthopedic supportive frame 10 is composed of the padded girt 11 preferably constructed of arcuate pieces 12 and 14 connected by means of separable hinges 14 and 15 supported on adjustable legs 16, 17, 18 and 19, which legs are firmly connected to the stabilizing base 21.

Girt 11 should be adjustable to heights of from about 36 inches to about 60 inches and this adjustment is provided by the telescoping leg construction shown in FIG. 3 in cooperation with extensible base members, the sliding arm extensions 22, disposed in recesses 23 located in the underside of platform 24 of base 21. Legs 16, 17, 18 and 19 are retained in position relative to the girt 11 by means of braces 25 interconnecting the legs and girt 11. At the bottom end thereof each of the adjustable legs

are connected to the base 21 by means of foot adapters 26 connected to sliding arms 22 in some convenient manner.

In the structure shown herein one of the foot members has a slot 27 formed therein to permit separation of the leg 19 therefrom by a swinging motion after removal of the pin from hinge 15. If desired, part 13 may be completely disconnected from part 12 by removing the pins from each of the separable hinges 14, 15. In like manner, braces 25 may be disconnected from girt 11 by movement of slotted connections and the entire unit can be quickly collapsed for ease of transport. Likewise, the sliding arms 22 can be easily moved into recessed position in slots 23 in the underside of platform 24 of stabilizer base 21 to take less room during carriage thereof.

In order to use the orthopedic supportive frame 10 it is necessary only to swing member 13 together with leg 19 to the position shown in dotted lines in FIG. 1 to enable introduction of the patient harnessed in long leg braces into the device in the erect position standing on platform 24. Closure of member 13 about the patient, reinsertion of the hinge pin in separable hinge 15 and reconnection of foot member 26 to the appropriate sliding arm 21 is all that is necessary to provide for the patient a secure erect location where he can freely use both his hands, wrists, arms and shoulders, his neck and his trunk muscles in complex movements requiring the use of multiple sets of muscles both in action and reaction without fear of injury from falls. Initially, to gain confidence the patient may only lean with his back against the girt 11 until he is satisfied that he is receiving full support from the stand 10 to prevent him from falling to any side. This confidence should become obvious to even the most insecure individual after a relatively short exposure within the supportive frame 10. After such confidence has been gained, the patient soon begins to make use of the full degree of freedom available in the stand. At the onset, the patient may wish girt 11 adjusted in the vicinity of the chest, but gradual improvement and confidence will enable commensurate lowering of the girt until it is in the region of the top of the hip bone. With the exception of the platform 24 of stabilizing base 21, which may be conveniently made of wood, and the padding for the girt 11, all parts are preferably made of a light metal, such as an aluminum alloy to provide a light, though strong, unit.

The fact that the full weight of the patient together with the additional weight of the long leg braces is directly and substantially vertically transmitted to the base 21 transforms the superstructure (legs, braces and girt) from an easily shiftable, and thereby unreliable, support for a paraplegic to a fully stable mechanism, which in cooperation with conventional long leg braces is able to supply total support for a paraplegic in a manner permitting considerable freedom of motion commensurate with the extent of the patient's increasing capabilities.

Although the superstructure is detachable from the stabilizing base, its use separate from the base is not contemplated, since the superstructure alone offers no reliable support to a patient still in need of leg braces above the knee, because of the danger of unintentional shifting of the superstructure precisely when the patient needs immovable support. Sideward shifting of the superstructure would be particularly dangerous to such a patient. Thus, by the time the paraplegic patient will have recovered sufficiently to profitably employ the superstructure apart from the stabilizing base, he will long since have been able to profitably employ conventional therapeutic exercise, e.g. parallel bars, wheel chair, mat exercises, physical therapist exercises and daily activity exercises, such as bathing.

Obviously modifications and variations of this invention are possible in the light of the above teachings. It is therefore to be understood that within the scope of the ap-

pended claims, the invention may be practiced otherwise than as specifically described.

What I claim as new and desire to secure by Letters Patent of the United States is:

1. An exercising device for maintaining in standing posture a human being, whose lower extremities are supported by separate artificial support means, during the performance of physical exercise during which a portion of the trunk of the human being is confined within an enclosing girding member, said device comprising in combination:
  - (a) an enclosing girding member subdivided into at least two connected arcuate pieces,
  - (b) at least three longitudinally-extending extensible support members connected to and depending from said girding member,
  - (c) stabilizer base means comprising a central platform and a plurality of base members affixed thereto and extensible therefrom, one of said extensible base members being connected to the lower extremity of each of said support members and
  - (d) hinge means connecting one of said arcuate pieces to the rest of said girding member,
    - (1) said one of said arcuate pieces having a single

support member depending therefrom and detachably connected to one of said extensible base members,

whereby by detaching said single support member from the extensible base member connected thereto, and rotating said one of said arcuate pieces and said single support member together about said hinge means, access may be readily provided into said girding member from the side.

2. The exercising device substantially as recited in claim 1 wherein the stabilizer base means is detachably connected to all the support members.
